(57) **CLAIM**

The ornamental design for an automated drug delivery device, as shown and described.

DESCRIPTION

FIG. 1 is a top perspective view showing the top, front, and one side of an automated drug delivery device showing our new design according to a first embodiment;

FIG. 2 is a front elevation view the first embodiment;

FIG. 3 is a rear elevation view of the first embodiment;

FIG. 4 is a side elevation view of the first embodiment;

FIG. 5 is a top plan view of the first embodiment.

FIG. 6 is a top perspective view showing the top, front, and one side of an automated drug delivery device showing our new design according to a second embodiment;

FIG. 7 is a front elevation view the second embodiment;

FIG. 8 is a rear elevation view of the second embodiment;

FIG. 9 is a side elevation view of the second embodiment;

and,

FIG. 10 is a top plan view of the second embodiment.

The broken lines showing an adhesive pad to which the automated drug delivery device may be attached form no part of the claimed design. In each embodiment, the left elevation view is identical to the right elevation view. In

(Continued)

each embodiment, the bottom is flat and unornamented, is not shown in the drawings, and forms no part of the claimed design.
